FOREIGN PATENT DOCUMENTS

CN 201630182132.0 * 8/2016

Primary Examiner — T Chase Nelson*Assistant Examiner* — Kelly L Gross(74) *Attorney, Agent, or Firm* — McClure, Qualey & Rodack, LLP(57) **CLAIM**

The ornamental design for an electrocardiogram recorder, as shown and described.

DESCRIPTION

FIG. 1 is a front perspective view of an electrocardiogram recorder in accordance with our new and ornamental design; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof, wherein the broken lines form no part of the claimed design; and,

FIG. 8 is a reference view showing the electrocardiogram recorder connected to a charger, and the charger and broken lines depicting its present environmental structure and form no part of the claimed design.

1 Claim, 6 Drawing Sheets(56)
